ELECTRIC CIRCUIT CONTROL MECHANISM

Martin A. Johnson, San Marino, Calif.

Application January 24, 1934, Serial No. 708,095

2 Claims. (Cl. 200—87)

My invention relates to mechanism especially adapted for controlling the contact points of an electric circuit in a signal system through the action of a power operated disc or wheel, in conjunction with an electro-magnet arranged in a separately controlled electric circuit; the present application covering subject matter divided out of my pending application Serial Number 682,251, filed July 26, 1933.

10 The purposes and advantages of my invention will be readily comprehended from the following detail description of the drawing, wherein:

Figure 1 is a diagrammatic view in elevation of my improved mechanism.

15 Figure 2 is a detail view in side elevation of the driven wheel of the mechanism, showing the side opposite to that disclosed in Figure 1.

The specific embodiment of the invention, as illustrated, involves a power driven disc or wheel 10 adapted to rotate in a given direction either through the medium of its shaft 11 or in any suitable manner. 12' represents a suitable armature arranged in an electric circuit, the leads whereof are shown at 13, and pivotally mounted at 14 is an armature 15 adapted to be attracted by the electro-magnet 12 when the latter is energized. The armature 15 is provided with a pair of contact springs 16 and 17 which normally are spaced apart or arranged in open position; the contact springs 16 and 17 are both provided with contact points 18 and 19, respectively, the contact springs being arranged in the electric circuit to be controlled, a portion of the lead line whereof is shown at 20 connected to spring 16; while the contact spring 17 is grounded as shown at 21.

The end of the pivoted armature 15 has a knurled wheel 22 journaled thereon so as to be free to rotate when the latter is brought into contact with the power operated disc or wheel 10.

40 One side of the knurled wheel 22 is provided with a coil spring 23, one end whereof is fixedly secured to the axle or spindle of wheel 22; (the spring being coiled thereabout) while the other end of the spring is fixedly secured to the armature 15; the normal tendency of the spring being to rotate wheel 22 back to normal position when the latter is free of the power driven disc or wheel 10.

Secured to the spindle or axle of wheel 22 are a pair of fingers 24 and 25; the fingers being 50 adapted to rotate with the spindle or axle to which wheel 22 is fixedly secured. Finger 24 is adapted to engage contact spring 16 and force its contact point 18 into contact with point 19 on spring 17; the latter spring being preferably of a 5 stiff type so as not to flex and to constitute a

stop for finger 25 when the wheel 22 is returned to normal position through the action of its coil spring 23.

It is assumed that power operated wheel 10 is rotating in clockwise direction and that the 5 circuit of electro-magnet 12 has been closed thus energizing the electro-magnet. Energizing the electro-magnet causes the armature 15 to be attracted toward the magnet and hence swing the free end of the armature toward the right in 10 Figure 1 thereby bringing the knurled wheel or disc 22 into operative relation with the disc or wheel 10, with the result that knurled wheel 22 will be rotated in counter-clockwise direction in Figure 1. Such counter-clockwise rotation of 15 wheel 22 will cause the finger 24 to swing to the left in Figure 1 and be brought into contact with contact spring 16 thereby closing a circuit which involves lead line 20.

As soon as the electric circuit of lead lines 13 20 and hence of electro-magnet 12 has been disrupted, it causes deenergization of magnet 12, allowing the armature 15 to swing back to normal position, moving wheel 22 out of contact with the power-driven wheel 10. As soon as wheel 22 has 25 been moved out of contact with wheel 10, the spring 23, which controls the spindle of wheel 22, will rotate the spindle and wheel 22 back to normal position, namely in clockwise direction in Figure 1, until finger 25 is brought into contact 30 with the stiff contact spring 17, thus preventing further rotation of the wheel; the contact spring 16 springing out of contact with the point of contact spring 17 as soon as finger 24 releases its pressure thereon. As a result the circuit controlled by springs 16—17 will be disrupted or 35 opened.

What I claim is:

1. In electric circuit control mechanism of the character described, a power operated wheel; an 40 electromagnet; a swingingly mounted armature adapted to be controlled by the electromagnet, said armature being provided with a pair of normally spaced electric circuit controlling contact points; a wheel rotatably mounted on said armature and adapted to be moved into operative engagement with the power operated wheel when the armature is attracted by said electromagnet; means carried by the second mentioned wheel 45 adapted to move said contact points into engagement with each other; and means whereby said second mentioned wheel and said first mentioned means are returned to normal position when said 50 electromagnet is deenergized and the armature swings back to normal position.

2. In electric circuit control mechanism of the character described, a power operated wheel; an electromagnet; a swingingly mounted gravity controlled armature provided with a pair of normally spaced circuit controlling contact points; a wheel rotatably mounted on the armature and adapted to be moved into operative engagement with the power operated wheel when the armature is attracted by said electromagnet; a pair of fingers adjustably secured to the spindle of the

second mentioned wheel, one of said fingers being adapted to move the contact points into engagement with each other when said wheel is rotated while the other finger constitutes a stop for said second mentioned wheel in its reverse rotation; and a coil spring whereby said second mentioned wheel is rotated to normal position when the electromagnet is deenergized and said armature swings back to its normal position. 5
